UNITED STATES PATENT OFFICE.

JOSEPH E. TILT, OF CHICAGO, ILLINOIS.

LAST.

1,145,945.

Specification of Letters Patent. Patented July 13, 1915.

Application filed February 20, 1915. Serial No. 9,518.

To all whom it may concern:

Be it known that I, JOSEPH E. TILT, a citizen of the United States, residing at Chicago, in the county of Cook and State of

Illinois, have invented a new and useful Improvement in Lasts, of which the following is a specification.

The primary object of my invention is to provide a construction of last which shall greatly reduce the expense for lasts in shoe-making, this being one of the largest items of expense in the manufacture of shoes, particularly those of the Goodyear welt variety, since the entire operation is carried on with the last in the shoe. With the more ordinary last, made entirely of wood, the great pressure required in attaching the heel on the shoe tends to crush the wooden last-heel and soon destroy it, thereby rendering the entire last unfit for further use.

My improvement involves forming the heel-portion of the last of metal, preferably solid and of a relatively light variety, such as aluminum, and the forward portion wholly of wood, and so joining the metal and wooden members that they shall be rigidly united for their conjoint use, but readily separable to enable the wooden member to be taken off and discarded when worn out and a new member of the same or of different shape as readily substituted on the same metal heel-member. In this way a supply in the factory of metal last-heels is practically everlasting, and only new supplies of the wooden members require to be provided, from time to time, thereby reducing the expense for lasts by about one-half, or even more, because the aluminum heel-pieces are worth, as scrap-metal, about one-half their original cost.

In the accompanying drawing, Figure 1 is a view in side elevation of a last of my improved construction; Fig. 2 is a longitudinal central vertical section of the same; Fig. 3 is a view in rear-end elevation of the forward or wooden member; Fig. 4 is a view in front-end elevation of the metal heel-member, and Fig. 5 is a broken plan view of the bottom of the last.

The heel 6 shown is a solid aluminum casting containing a socket 7 in its top to fit on a standard, as usual, and having a wooden peg 8 confined centrally in its bottom and a similar peg 9 in its back for driving into them the usual tacks in making a shoe on the last. A recess 10 is formed in the front face

of the metal heel-member 6 and through the latter extends, from nearly the lower end of its back to about the center of its recessed face, a hole for a bolt 11 having its head countersunk into the back. A reinforcing plate 12 of relatively hard metal, as steel, is securely fastened, as by screws 13, to the bottom of the metal heel, to cover the same, and projects at its forward edge, as a lip, slightly beyond the front face of the heel-member. The wooden member 14, formed with the usual separable instep-section 14^a held in place near its forward end by a wooden pin 15 and at its rear end by the head of a screw 16, or other suitable means, contains a bolt-hole as a continuation of the inclined hole in the metal heel for the bolt 11, which latter, when the two members are brought together to form the last, is passed through the wooden member to project into a recess 17 in the latter admitting the nut for tightening the bolt in place. When the two parts are being thus united, or taken apart, the instep-section is removed, and it contains a recess 17^a in its under side to register with the recess 17 and house the nut-carrying end of the bolt. The rear face of the wooden member is formed with a shoulder 18 conforming to and snugly fitting the recess 10, which it enters, in bringing the two members together for uniting them, to prevent the wooden member from being strained out of its true position under the heavy pressure which is applied on the sole of the shoe in the process of leveling. The forward lip on the plate 12 fits into an offset in the rear lower edge of the member 14, as shown, and bridges the joint at the bottom of the two members.

As will readily be seen, the manner of fastening the two members of the last together facilitates the fastening as well as the separating operation, since all that is required for either purpose, after removing the instep-block, is to manipulate a single bolt rigidly and securely holding the members in their co-operative relation when supplemented by the shoulder 18 in the recess 10.

What I claim as new and desire to secure by Letters Patent is:—

1. A last comprising a forward wooden member provided with a separable instep-section and containing a recess beneath said section, a metal heel-member, a bolt extending from the heel-member through the

wooden member into said recess, and a nut on the bolt in said recess.

2. A last comprising a forward wooden member provided with a separable instep-section and containing a recess beneath said section and an oblique bolt-hole leading to said recess, a metal heel-member containing an oblique bolt-hole, to register with said

bolt-hole in the wooden member, a bolt passing through said registering bolt-holes, and 10 a nut on the end of the bolt in said recess.

JOSEPH E. TILT.
